UNITED STATES PATENT OFFICE

2,506,771

ADJUSTABLE LOUVER OPERATOR

Lemual G. Brown, Oklahoma City, Okla.

Application August 30, 1948, Serial No. 46,748

8 Claims. (Cl. 268—96)

1

The present invention relates to metal awnings of the pivoted louver type, and more particularly to operating or control mechanism for the louvers of such awnings.

The present invention is an improvement over my pending application Serial Number 597,010, filed June 1, 1945.

In crank operated louver controls, it is usually necessary to bore a transverse hole through the bottom rail of the fly-screen frame, so that the shaft portion of the crank may engage the control mechanism. In some cases the hole is bored through the apron of a window frame, and also through the fly-screen rail. Since the awning frame which pivotally mounts the louvers must be positioned in a certain position with relation to the window opening, it frequently occurs that the bored hole or holes fail to properly align with the crank socket of the control mechanism.

When this condition arises, the bore holes must either be re-located or enlarged to accommodate the discrepancy.

The prime object of the present invention, is to provide a louver control mechanism which is carried by the awning frame outside of the fly-screen frame, and which is shiftable to accommodate ordinary mis-alignment of the bore hole with the crank socket.

Another object is to provide a louver control mechanism which is so designed that frictional tension may be applied selectively to the mechanism in order to retain the louvers in their various adjusted positions.

A further object is to provide a very simple mechanism for accomplishing the purposes set forth hereinabove.

An additional object is to provide a louver control mechanism, which is so designed that it is comparatively cheap to manufacture, is simple to install, and which has few moving parts to become worn or to get out of order.

Other objects will be apparent from the following description when taken in conjunction with the accompanying three sheets of drawings, wherein:

Figure 1 is a fragmentary perspective view of the lower right hand corner portion of an awning frame, looking outwardly at its inside surface, and showing the control mechanism of the present invention operatively installed thereon;

Figure 2 is a fragmentary plan view, partially in horizontal section, and illustrating the awning frame in its installed relation to a conventional fly-screen and window frame;

Figure 3 is a vertical sectional view taken substantially along the line 3—3 of Fig. 2;

Figure 4 is a view similar to Fig. 1, but showing the louvers in their closed instead of partially opened positions, and showing the control mechanism in its corresponding position;

2

Figure 5 is an enlarged fragmentary perspective view showing a slightly different embodiment of the invention;

Figure 6 is a vertical view taken longitudinally through the mechanism of Fig. 5; and

Figure 7 is a fragmentary vertical sectional view taken through a fly-screen rail and window frame opening, and illustrating vertical adjustability of the operating crank.

Like characters of reference designate like parts in those figures of the drawings in which they occur.

In the drawings:

The reference numeral 1 indicates, as a whole, a conventional awning frame which is usually rectangular in outline, and which is composed of two parallel vertically disposed side members, a top member extending between and rigidly connecting the upper ends of said side members, and which has a horizontal bottom member or sill which extends between and rigidly connects the lower ends of the two side members.

In the accompanying drawings, only the lower portion of the right hand side member, and the right hand end portion of the sill member is shown. The side member shown is indicated, as a whole, by the reference numeral 2, and the sill member is indicated in its entirety by the numeral 3.

The two frame members 2 and 3 are substantially conventional, except that the inside edge of the sill member 3 is provided with an upstanding flange 4 which extends throughout the entire length of the sill.

As is usual with louver-type awnings, there is provided a plurality of horizontally disposed louvers 5 which span the central opening or space described by the frame 1, such louvers having perpendicularly bent end flanges or ears 6 at both ends of each, such ears being pivotally connected to the side members by suitable rivets or pivot pins 7. The ears 6 of similar ends of the louvers are each pivotally connected by a pivot pin 9 to a vertically disposed actuating bar 8, which when shifted vertically, acts to partially rotate the louvers simultaneously upon their respective pivot pins 7. The louvers are so arranged with relation to each other, that when the bar 8 is lowered, their edge portions 10 are swung outwardly to leave spaces between the louvers, and when the bar is raised, said louver edges 10 simultaneously swing downwardly to overlap the upper edge of the next louver therebelow. The upper edges of the louvers are indicated by the reference numeral 11.

With the exception of the flange 4 of the sill member 3, the elements which are above described, and which are indicated by the reference numerals 1 to 11 inclusive, are more or less conventional, or at least, are disclosed in my above

mentioned patent application Serial Number 597,010.

The actuator of the present invention is adapted to function in connection with the above described awning frame 1, the louvers 5, and the actuating bar 8, and consists substantially of the following described parts or elements.

A loop-like strap metal bracket 20 is provided for installation upon the upper surface of the sill member 3. The bracket 20 consists of an elongated flat plate portion 21 having an elongated through slot 22 adjacent its left hand end, as viewed in the drawings. The bracket further consists of a loop formed by a continuation of the strap metal plate portion 21. The loop has a flat bottom 23, an arcuate end wall 24, a flat top 25, and a perpendicular end wall 26. The lower end edge of the end wall 26 rests upon and is preferably spot welded to the plate portion 21.

The bottom 23 and top 25 of the loop are alignedly perforated to receive a clamping bolt 27 which has a threaded end adapted to receive a nut 28. The offices of the bracket 20 and bolt 27 are more fully described hereinbelow.

Disposed within the loop of the bracket 20, and normally movable therein, is a cylindrical crank-socket 29 having a polygonal bore 30 therein. The crank socket 29 continually lies in a horizontal position, but may be shifted to various degrees with relation to the longitudinal axis of the bracket 20.

The flat portion 21 of the bracket 20 is pivotally connected to the sill 3 of the awning frame 1 by a suitable bolt 31 passing through the slot 22, and having a nut 32 by which the portion 21 may be clamped to the sill. The arrangement is such that the bracket 20 may be bodily shifted longitudinally along the sill 3, or it may be moved pivotally with relation to said sill. In both events, the bracket may be selectively anchored to the sill by tightening the nut 32.

By tightening the nut 32 on the bolt 27, the top 25 of the loop may be caused to frictionally engage the crank-socket 29. This frictional tension may be either increased or decreased at will by proper manipulation of the nut 28.

The crank-socket 29 has a rigid arm 33 projecting from its exterior surface intermediate the ends thereof, and the outer end of the arm 33 is through perforated to receive a pivot pin 34. An arcuate link 35 has its lower end pivotally connected to the pin 34, and its other end is pivotally connected to the actuating bar 8 by a suitable bolt 36.

Pivotal movement of crank-socket 29 in a clock-wise direction, causes the arm 33 to swing downwardly from its position as shown in Fig. 4, and such movement of the arm 33 also causes downward movement of the actuating bar 8. The sill 3 has an elongated through slot 37 which acts as a relief to permit downward movement of the arm 33.

The arm 33 is equipped with a rigid leg 38 which is adapted to contact the sill 3 and limit pivotal movement of the crank-socket in a counter clock-wise direction.

In Fig. 2, the awning frame 1 is illustrated as being mounted to a conventional fly-screen frame, with the reference numeral 39 indicating the bottom cross-member of the fly-screen frame. In said Fig. 2, the reference numeral 40 indicates the bottom cross-member of a conventional window frame against which the fly-screen frame is mounted. When the awning frame is thus

mounted, the flange 4 of the sill 3 lies against the outer surface of the fly-screen frame.

In order to actuate the crank-socket 29 to partial rotation, the two cross-members 39 and 40 are alignedly perforated to permit the passage therethrough of the shank portion 41 of a suitable hand operated crank 42. The end of the shank portion 41 is made polygonal to coincide with and removably fit within the bore 30 of the crank-socket 29.

In installing the control mechanism of the present invention, it is preferable that the bore holes in the cross-members 39 and 40 be positioned in axial alignment with the crank-socket 29, when the crank-socket is disposed at right angles to the flange 4 of the sill 3. However, inaccuracy may, and usually does occur to some degree, with mis-alignment resulting. Should the holes be found to have been bored perpendicular to the cross-members 39 and 40, but to one side of the crank-socket, then the bracket 20 may be bodily shifted to obtain proper registry of the holes and the bore of the crank-socket. Should it be found that the holes have been bored other than at right angles to the cross-members 39 and 40, then the crank-socket may be adjustably shifted in the loop of the bracket 20. In either event, compensation is possible for any horizontal inaccuracy in boring the holes through the members 39 and 40.

The connections of the arm 33, pin 34 and link 35 are left sufficiently loose to permit the shifting of the crank-socket 29 within reasonable limits.

35 By selectively tightening or loosening the nut 28 on the clamping bolt 27, proper frictional tension may be placed on the crank-socket to insure the louvers 5 remaining in place, once they have been pivotally set. The same control mechanism 40 may therefore be used on awnings having different numbers of louvers, or having louvers of different lengths.

In Fig. 2, the variance in the position of the bore holes have been purposely exaggerated over conditions which the mechanism would ordinarily be called upon to accommodate.

In Figs. 1 to 4 inclusive is shown an embodiment of the invention which is capable of compensating for horizontal discrepancy in the bore holes through the fly-screen member 39 and the window frame number 40. It is obvious that vertical variation might also well occur in boring said holes, and that it would therefore be desirable to provide for the accommodation of such variation. With this object in view, the embodiment of Figs. 5, 6, and 7 has been provided.

In Figs. 5 and 6, the portion 21 of the bracket 20 is curved upwardly as indicated by the reference numeral 43, thus raising the loop portion of the bracket a slight distance above the sill 3 of the awning frame 1. In this embodiment, it is preferable that the bracket 20, or at least the portion 21 thereof, be made of tempered steel, so that it will have inherent resiliency tending to normally maintain the loop in its spaced relation above the sill 3. The loop of the bracket may therefore be moved either toward or away from the sill 3 by distorting the bent portion 43 against its inherent resiliency.

In order that the loop end of the bracket 20 may be sprung downwardly into flat contact with the upper surface of the sill 3, the sill is provided with a perforation or hole 44. The hole 44 is located directly beneath the head of the clamp-

ing bolt 27, so that the head may enter the hole when the bracket is sprung downwardly.

By springing the bracket either upwardly or downwardly, compensation is furnished for vertical variation in boring the holes through the horizontal frame members 39 and 40. The crank socket 28 may therefore be aligned with the bore holes through the frame members 39 and 40, and thereafter, the shank 41 of the crank 42 may be easily inserted at will.

In order to control the vertical relationship between the bracket 20 and the sill 3, adjusting screws 45 and 46 are provided. The screws are threadedly engaged respectively with the bracket portion 24 and the sill 3, and their adjustment is thought to be obvious.

Obviously the invention is susceptible to some change or alteration without defeating its practicability, and I therefore do not wish to be confined to the preferred embodiment shown in the drawings and described herein, further than I am limited by the scope of the appended claims.

I claim:

1. The combination with a window awning consisting of a rigid frame pivotally supporting a plurality of horizontal louvers, and wherein a vertically reciprocal actuating bar acts to pivotally move the louvers simultaneously, of means for manually controlling movement of the bar, including: a loop-like bracket of spring material adapted to lie in a substantially horizontal position above the bottom horizontal member of said frame; means for laterally pivoting the bracket in such position on a vertical axis; a horizontal rotatable crank-socket passing through the loop of said bracket and movable therein to various angles with relation to the frame; means for retaining the socket in various horizontal positions of adjustment while allowing its rotation; a perpendicular arm carried by the socket; a link having one end pivotally connected to the outer end of said arm; an operative connection between the other end of said link and said louver actuating bar; and a removable crank adapted at one end to be inserted into said socket for rotating the same within said bracket loop.

2. The combination with a window awning consisting of a rigid frame pivotally supporting a plurality of horizontal louvers, and wherein a vertically reciprocal actuating bar acts to pivotally move the louvers simultaneously, of means for manually controlling movement of the bar, including: a loop-like bracket adapted to lie flatly upon the bottom horizontal member of said frame; means for pivoting the bracket in such position on a vertical axis; a horizontal rotatable crank-socket passing through the loop of said bracket and movable therein to various angles with relation to the frame; means for adjustably creating frictional tension between said bracket loop and the socket; a link having one end pivotally connected to the outer end of said arm; an operative connection between the other end of said link and said louver actuating bar; and a removable crank adapted at one end to be inserted into said socket for rotating the same within said bracket loop.

3. Structure as specified in claim 1, in which the bracket pivoting means allows longitudinal shifting of the bracket along said horizontal member, and means for retaining the bracket in various horizontal positions of adjustment with relation to said horizontal frame member.

4. Structure as specified in claim 1, and means

for limiting rotation of the crank-socket in one direction.

5. Structure as specified in claim 2, in which said tension creating means includes: a bolt extending through the top and bottom walls of the loop; and a nut on the bolt for bending one of said walls.

6. The combination with a window awning consisting of a rigid frame pivotally supporting a plurality of horizontal louvers, and wherein a vertically reciprocal actuating bar acts to pivotally move the louvers simultaneously, of means for manually controlling movement of the bar, including: a loop-like bracket of spring material adapted to lie in a substantially horizontal position above the bottom horizontal member of said frame; means for laterally pivoting the bracket in such position on a vertical axis; a horizontal rotatable crank element passing through the loop of said bracket and movable therein to various angles with relation to the frame; means for retaining the element in various horizontal positions of adjustment while allowing its rotation; a perpendicular arm carried by the element; a link having one end pivotally connected to the outer end of said arm; and an operative connection between the other end of said link and said louver actuating bar.

7. The combination with a window awning consisting of a rigid frame pivotally supporting a plurality of horizontal louvers, and wherein a vertically reciprocal actuating bar acts to pivotally move the louvers simultaneously, of means for manually controlling movement of the bar, including: a loop-like bracket adapted to lie flatly upon the bottom horizontal member of said frame; means for pivoting the bracket in such position on a vertical axis; a horizontal rotatable crank element passing through the loop of said bracket and movable therein to various angles with relation to the frame; means for adjustable creating frictional tension between said bracket loop and the element; a link having one end pivotally connected to the outer end of said arm; and an operative connection between the other end of said link and said louver actuating bar.

8. The combination with a window awning consisting of a rigid frame pivotally supporting a plurality of horizontal louvers, and wherein a vertically reciprocal actuating bar acts to pivotally move the louvers simultaneously, of means for manually controlling movement of the bar, including: a loop-like bracket of spring material pivotally affixed to the frame for transverse swinging movement with relation to the frame; an elongated crank element passing through the loop of said bracket and movable therein to various angles in relation to the frame; means for retaining said element in various positions of angular adjustment while allowing its rotation; a perpendicular arm carried by said element; a link having one end pivotally connected to the outer end of said arm; and operative connections between the other end of the link and said louver actuating bar.
